GUN FOR HOMOGENIZING AND AERATING
A FLOWING STREAM OF PLASTICIZED
ADHESIVE MATERIAL

Max M. True, Tulsa, Okla.

Application April 17, 1953, Serial No. 349,345

3 Claims. (Cl. 259—151)

1

This invention relates to a gun for homogenizing and aerating a flowing stream of plasticized adhesive material containing aggregates and for projecting said aggregate bearing adhesive onto a surface.

Prior attempts to project a plasticized adhesive material containing aggregates onto a surface to coat the surface while having been moderately successful have not proven to be entirely satisfactory owing to the fact that no matter how thoroughly the material was mixed and homogenized prior to its delivery to the surface, the differences between the specific gravities or weights of the ingredients would tend to cause a separation or segregation of the materials before they could be delivered to the surface to be coated.

The primary object of this invention is to effect in the gun employed to direct the material against the surface an aeration and homogenization of the coating material.

Another object is to effect the homogenization and aeration of the material immediately prior to its projection onto the surface not only to assure even distribution of the aggregates through the adhesive vehicle but to so lighten the mixture that its even distribution on the surface is assured.

The above and other objects may be attained by employing this invention which includes among its features a body having a discharge passage opening through one end thereof, convergent passages which open at their convergent ends into the discharge passage, means opening through the opposite end of the body and communicating with the divergent ends of the convergent passages for directing a plasticized adhesive material containing aggregates into the convergent passages, a bore extending through the body above the divergent ends of the convergent passages, an air inlet port extending through the top of the body and communicating with the bore, an air discharge passage in the body between the convergent passages and opening toward the discharge passage adjacent the convergent ends of the convergent passages, a duct extending through the body and establishing communication between the bore and the discharge passage, aerating and homogenizing ports in the body and opening into the convergent passages in axial alignment therewith through the divergent ends thereof, ducts extending through the body and establishing communication between the bore and the aerating and homogenizing ports and a turning plug in the bore and having ports therein which establish communication with the ducts.

2

In the drawings

Fig. 1 is a plan view of a gun embodying the features of this invention,

Fig. 2 is a side view of the gun illustrated in

5 Fig. 1,

Fig. 3 is a rear end view of the gun,

Fig. 4 is a longitudinal sectional view taken substantially on the line 4—4 of Fig. 1,

Fig. 5 is a longitudinal sectional view taken substantially on the line 5—5 of Fig. 2,

10 Fig. 6 is a sectional view taken substantially on the line 6—6 of Fig. 2, and

Fig. 7 is a sectional view taken substantially on the line 7—7 of Fig. 1.

15 Referring to the drawings in detail this improved gun designated generally 10 comprises an elongated body 12 having a discharge package 14 opening through one end. Formed in the body 12 are convergent passages 16 which open at their convergent ends into the discharge passage 14 and communicate through curved passages 18 with an axial bore 20. The passages 16 and 18 together with the bore 20 define within the body 12 a post 22 which extends perpendicular to the longitudinal axis of the body 12. The side of the post 22 which faces the bore 20 is flattened as at 24 to define a bearing surface for the rotary valve to be more fully hereinafter described.

Extending transversely through the body 12 above the divergent ends of the passages 16 is a bore 26 and opening through the top of the body 12 above the bore 26 and communicating therewith is an air inlet port 28. An air discharge passage 30 extends through the post 22 in axial alignment with the discharge passage 14 and has communication with the bore 26 through an air passage 32. A plug 34 closes the end of the passage 30 adjacent the bearing surface 24 so as to cause air entering the passage 30 to be discharged into the discharge passage 14 so as to project the material passing through the convergent passage 16 through the nozzle 36 of the gun and onto the surface to be coated.

45 Opening into the curved passages 18 in axial alignment with the convergent passages 16 are jet ports 38 which communicate through ducts 40 with the bore 26. One end of the bore 26 is closed by a cover plate 42 and removably secured to the body 12 in closing relation to the opposite end of the bore 26 is a cover plate 44 having an axial opening 46 extending therethrough in which a stem 48 is mounted to rotate. A tubular valve or turning plug 50 is carried by the stem 48 for rotation therewith in the bore 26 and extending through the turning plug 50 intermediate the 50 ends thereof is a port 52 which establishes com-

munication between the port 28 and the interior of the turning plug and also with the port 28 and the passage 32. Ports 54 extend through the turning plug 50 adjacent opposite ends thereof and establish communication between the interior of the turning plug and the passages 40. A hand wheel 56 is detachably connected in any conventional manner with the stem 48 for rotation therewith so that upon turning the hand wheel 56 the turning plug 50 may be rotated to select the positions of the ports 52 and 54 with relation to the passages 32 and 40.

The end of the body 12 through which the bore 20 opens is externally screw threaded as at 58 and extending through the body 12 adjacent the threads 58 is a slot 60. A valve body 62 is mounted in the bore 20 to rotate about the longitudinal axis of the body 12 with its inner end seated against the bearing surface 24 and is held in place therein for rotation about the longitudinal axis of the body 12 by an internally screw threaded retaining ring 64 which threadably engages the threads 58 on the body 12. Secured as by cap screws 66 (Fig. 7) to the valve body 62 for movement in the slot 60 is a stop 68 by means of which rotary movement of the valve body 62 within the bore 20 is restricted. The end of the valve body 62 remote from the bearing surface 24 is externally screw threaded as at 70 for coupling to a supply of plasticized adhesive material and extending axially into the valve through the threaded end thereof is an inlet passage 72 which communicates through diametrically opposite ports 74 with the curved passages 18.

In use the valve body 62 is coupled by its threaded end 70 to a source of plasticized adhesive material containing aggregates and the port 28 is coupled to a source of air pressure. Upon rotating the valve 62 to align the ports 74 with the curved passages 18 the material will flow through the passages 16 in first divergent and then convergent streams about the post 22. By turning the hand wheel 56, the turning plug 50 may be moved to bring the ports 54 into registry with the passages 40 so as to direct jets of air through the jet ports 38 and into the cores of the streams of material passing through the convergent passages 16 to aerate and homogenize said material. As the aerated and homogenized material issues from the convergent passages 16 it enters the discharge passage and is propelled therethrough and projected onto the surface to be coated by the air passing through the air discharge passage 30. Obviously if so desired a plate 76 having a discharge opening 78 of a selected cross section may be attached to the gun adjacent the discharge nozzle to enable the material to be directed onto the work in any desired manner.

What is claimed is:

1. A gun for homogenizing and aerating a flowing stream of plasticized adhesive containing aggregates and for projecting said aggregate bearing adhesive onto a surface, said gun comprising an elongated body having an axial recess extending therewith through one end thereof, said body having a transverse slot opening through the side thereof and communicating with the recess intermediate the ends thereof, said body having oppositely disposed curved passages therein which communicate with the recess in diametrically opposed relation and convergent passages therein which open into the curved passages remote from the recess, said body having a discharge passage opening through the end thereof remote from the

recess which discharge passage communicates with the convergent passages adjacent the convergent ends thereof, a turning plug mounted in the recess to rotate about the axis thereof, said turning plug having an inlet passage opening through the end thereof remote from the body and also having diametrically opposed openings extending through the wall adjacent the inner end thereof for establishing communication between the inlet passage and the curved passages, means carried by the turning plug and extending through the slot for rotating said turning plug in the recess and selectively registering the openings with the curved passages, said body having jet passages therein which open into the curved passages in axial alignment with the convergent passages for introducing homogenizing and aerating air into plasticized adhesive material flowing through said passages, and said body having an air passage disposed therein which aligns with the axis of the discharge passage for directing an air blast against homogenized and aerated adhesive material issuing from the convergent passages and propelling said material through the discharge passage and onto a surface.

2. A gun for homogenizing and aerating a flowing stream of plasticized adhesive containing aggregates and for projecting said aggregate bearing adhesive onto a surface, said gun comprising an elongated body having a discharge passage extending therewith through one end thereof, said body having convergent passages therein which open into the discharge passage and define between them a post, said post having an air discharge passage extending therethrough in axial alignment with the discharge passage, means mounted in the body adjacent the end thereof remote from the discharge passage for selective communication with the convergent passages adjacent the divergent ends thereof, said body having jet passages therein which align axially with the convergent passages adjacent the divergent ends thereof for directing jets of aerating and homogenizing air into plasticized adhesive material passing through the convergent passages, said body having a bore extending transversely therethrough above the divergent ends of the convergent passages and a duct opening into the bore and communicating with the air discharge passage, said body also having ducts therein which open into the bore and communicate with the air discharge passage in the post for conveying air to and against the aerated and homogenized adhesive to project said adhesive through the discharge passage and against a surface to be coated, and said body having an air inlet port opening through its top and communicating with the bore.

3. The structure defined in claim 2, a tubular turning plug mounted in the bore to rotate about the longitudinal axis thereof, and said turning plug having ports extending therethrough for simultaneously establishing communication between the air inlet port and the air ducts.

MAX M. TRUE.
